(57) **CLAIM**

The ornamental design for a foldable scale, as shown and described.

DESCRIPTION

FIG. 1 is a top perspective view of a foldable scale in an unfolded configuration according to an embodiment;

FIG. 2 is a bottom perspective view of the foldable scale in the unfolded configuration;

FIG. 3 is a top elevational view of the foldable scale in the unfolded configuration;

FIG. 4 is a front elevational view of the foldable scale in the unfolded configuration;

FIG. 5 is a left side elevational view of the foldable scale in the unfolded configuration;

FIG. 6 is a bottom elevational view of the foldable scale in the unfolded configuration;

FIG. 7 is a rear elevational view of the foldable scale in the unfolded configuration;

FIG. 8 is a right side elevational view of the foldable scale in the unfolded configuration;

FIG. 9 is a top perspective view of the foldable scale in a semi-folded configuration;

FIG. 10 is a bottom perspective view of the foldable scale in the semi-folded configuration;

FIG. 11 is a left side elevational view of the foldable scale in the semi-folded configuration;

FIG. 12 is a right side elevational view of the foldable scale in the semi-folded configuration;

FIG. 13 is a front elevational view of the foldable scale in the semi-folded configuration;

FIG. 14 is a rear elevational view of the foldable scale in the semi-folded configuration;

FIG. 15 is a bottom elevational view of the foldable scale in the semi-folded configuration;

FIG. 16 is a top elevational view of the foldable scale in the semi-folded configuration;

FIG. 17 is a top perspective view of the foldable scale in a folded configuration;

FIG. 18 is a bottom perspective view of the foldable scale in the folded configuration;

FIG. 19 is a front elevational view of the foldable scale in the folded configuration;

FIG. 20 is a rear elevational view of the foldable scale in the folded configuration;

FIG. 21 is a bottom elevational view of the foldable scale in the folded configuration;

FIG. 22 is a top elevational view of the foldable scale in the folded configuration;

FIG. 23 is a left side elevational view of the foldable scale in the folded configuration; and,

(Continued)

FIG. 24 is a right side elevational view of the foldable scale in the folded configuration.

In FIGS. 1-24, contour lines and shading shown in the drawings are intended to represent the approximate three-dimensional contours of the design, and are not intended to indicate surface decoration. The broken lines shown in the drawings are for illustrative purposes only and form no part of the claimed design.
